UNITED STATES PATENT OFFICE.

ALEXUS C. LINDGREN, OF MOLINE, ILLINOIS, ASSIGNOR TO MOLINE PLOW COMPANY,
A CORPORATION OF ILLINOIS.

TWO-ROW CULTIVATOR.

970,513.

Specification of Letters Patent. Patented Sept. 20, 1910.

Application filed September 30, 1908. Serial No. 455,465.

To all whom it may concern:

Be it known that I, ALEXUS C. LINDGREN, of Moline, county of Rock Island, and State of Illinois, have invented a new and useful 5 Improvement in Two-Row Cultivators, of which the following is a specification.

This invention relates to wheeled cultivators of the type in which the beams or drag bars are sustained by a wheeled frame 10 in such manner that they may be shifted laterally by the feet of the driver to follow deviations in crooked rows, and is designed for the cultivation of two rows at one time, such machines being known in the art as 15 "two-row cultivators", and embodying two pairs or sets of beams or cultivating devices, operating respectively on opposite sides of the two rows.

The invention consists of various improvements in machines of this type, which improvements are directed more particularly to form and construction of the supporting frame; the manner of mounting the beams thereon, so that they may be shifted 25 laterally; the form and construction of the mechanism for controlling the lateral movements of the beams; the means for varying the distance between the two sets of beams; and various other features of construction 30 which will be fully described in this specification, and the novel parts pointed out in the claims.

In the accompanying drawings:—Figure 1 is a top plan view of my machine. Fig. 2 35 is a rear elevation of the same. Fig. 3 is a front elevation. Fig. 4 is a side elevation with the near ground wheel removed. Fig. 5 is a longitudinal sectional elevation on the line a—a of Fig. 1. Fig. 6 is a perspective 40 view showing the manner of supporting and adjusting the beams at their forward ends transversely.

Referring to the drawings:—1 represents a wheeled frame comprising a long main 45 axle-member 2, provided on its ends with depending bracket-arms 3, containing vertical lining sockets 4 and 5, in which are loosely mounted the vertical stems 6 of the stub-axes 7, having mounted on their ends 50 ground wheels 8, which construction permits the ground wheels to swivel or turn relatively to the axle-member on vertical axes, the purpose of which will presently appear. The axle-member is in the form of 55 two parallel bars 2^a disposed on edge and

spaced apart by means of the depending brackets at their ends, which brackets are seated and secured between the bars; and by central depending bracket 9 seated and secured between the bars at this point, as 60 shown in Fig. 5, the said axle-member being braced and strengthened by means of a truss rod 10 fixed at its ends in eyes on the upper ends of the end brackets, and extending thence downward between the bars 2^a and 65 through the central bracket 9. Connected at their rear ends to the axle-member are two tongues 12, braced and held fixedly in position by means of four brace rods 12^a, 12^b, 12^c, and 12^d, the rods 12^a and 12^d being 70 fixed at their rear ends to the outer ends of the axle member, and at their forward ends to the outer sides of the two tongues respectively, while the brace rods 12^b and 12^c are connected at their rear ends to the axle- 75 member near its center, and at their forward ends to the inner sides of the two tongues respectively, a horizontal frame bar 13 being extended transversely beneath the tongue and brace bars, and fixed firmly 80 thereto, as shown in Fig. 1.

14 represents a driver's seat sustained on the rear end of a seat frame comprising two longitudinally extending bars 14^a extending above and resting on the axle-member, with their forward ends fixed to the brace rods 12^b and 12^c respectively. 85

15 represents a transversely extending beam supporting member, formed with two arched portions to straddle the two rows of 90 plants, and three depressed horizontal beam-attaching portions, two outer ones, 15^a and 15^b, and a long central one, 15^c, the two inner beams, 16 and 16^a, being connected with the central depressed portion, while the outer 95 beams 16^b and 16^c are connected to the outer portions, the connection of said beams with the supporting member being such that they may slide horizontally thereon to a limited extent and may also be raised and 100 lowered at their rear ends. The beam supporting member is sustained so as to move transversely back and forth, by means of three suspension straps A, B and C, jointed at their upper ends to the transverse frame 105 bar 13, and pivotally connected at their lower ends to the beam support, the latter being thus suspended from the frame and capable of an oscillating motion trans- 110 versely, which motion is controlled by the

feet of the driver through the medium of a foot-lever mechanism presently to be described, by which means he is enabled to shift the beams laterally to follow with certainty the rows of plants under cultivation.

- 5 In order that when the beam support is moved laterally, the ground wheels may be turned to cause the machine to follow the direction of the rows, I connect the ends 10 of the beam support with the swiveling wheels by means of longitudinally extending brackets or arms 17 and 17^a, the rear ends of which are fixed to the vertical stems 15 of the stub-axles, while their forward ends are jointed, by means of vertical pivot bolts 18 and 18^a, between rearwardly extending arms 19 on two yoke frames 20, fixed respectively to the ends of the beam support, the brackets 17 and 17^a thus forming a "parallel 20 motion", whereby the beam support is guided in its oscillations and maintained at all times transversely with reference to the line of draft, thereby causing the beams to maintain their longitudinal alignment, with 25 the cultivating devices facing squarely in the direction of travel. As a result of this construction, the oscillations or lateral movements of the beam support will shift the forward ends of the brackets 17 and 17^a 30 and will swivel the vertical stems of the stub-axles in their bearing sockets of the frame, and thereby correspondingly turn the ground wheels to the right or left, as the case may be.
- 35 The mechanism by which the driver controls the lateral movements of the beam support, consists of a horizontally arranged foot lever 21 pivoted midway between its ends on a vertical axis on a longitudinally extending 40 link 22, which link is in turn pivoted on a vertical axis to the lower end of the bracket 9 and at its forward end to a bracket plate 22^a fixed to the center of the beam support. This foot lever extends outwardly and rearwardly from its point of pivotal connection 45 with the link, and is provided on its ends with foot rests for the driver's feet. On opposite sides of its axis, it is connected, by means of two forwardly and outwardly extending rods 23 and 23^a, with the two arched portions respectively of the beam support, so that when the foot lever is rocked on its axis, it will act to push endwise on the beam support through one of the connecting rods, and 50 pull endwise in the same direction on the beam support through the other connecting rod, with the result that the support will be shifted laterally and will correspondingly shift the beams, the foot lever at the same 55 time moving bodily transversely, by reason of its connection with and support by the pivoted link 22, before alluded to. The beams are each in the form of two parallel beam-bars, fixed at their forward ends to 60 connecting heads mounted loosely on the de-

pressed portions of the beam support, so that they may be moved laterally on said support, as above described, and may be also raised vertically at their rear ends, suitable means being provided for tying or connecting the 70 beams together transversely, and for the time being connecting them with the beam support, so as to prevent a relative motion between the two in the lateral movements of the support, for the purpose of causing the 75 beams to be moved positively with the support. This connection of the parts is effected by the provision of connecting devices 24 between the inner beams, which connecting devices are movable laterally with the beam 80 support and which serve as a means for transmitting the motion of the support to the beams. Additional connecting devices 25 are provided between the inner beams and the outer beams of the respective pairs, whereby 85 the motion transmitted to the inner beams will, through these additional connecting devices, be transmitted to the outer beams, with the result that they will all be caused to move together with the beam support when 90 the latter is shifted transversely. The connecting devices 24 are so formed as will be presently described that the distance between the two pairs of beams may be varied at will, while the connecting devices 25 are of such 95 form that, while causing the outer beams to move with the inner beams, these devices will admit of an independent adjustment of the outer beams with reference to the inner beams.

100 Connecting devices 24 for the inner beams comprise two transverse links 24^a jointed at their outer ends to the two beams respectively, and formed at their inner ends with holes through which extends a finger 24^b on the forward end of an arm 24^c, fixed to the lower end of a vertical lever 24^d pivoted to a segment frame 24^e, fixed to and movable with the pivotal link 22, before alluded to, the lever being provided with a locking dog 110 adapted to engage teeth on the segment frame for the purpose of locking the parts in the position adjusted. By the movements of the lever back and forth, the arm 24^c will be raised and lowered, and acting on the inner ends of the two transverse links, will draw or fold them together, or extend them outward, thereby correspondingly drawing the two beams together, or separating them, the beams being held in the adjusted position by means of the locking dog.

115 The connecting devices 25 consist of yokes or arches 25^a jointed at their inner ends to the inner beams, and adjustably connected at their outer ends with the outer beams by means of spring actuated locking pins 25^b on the beams, engaging horizontal toothed arms 25^c on the outer ends of the yokes, the yokes when locked by the pins causing the outer beams to move with the inner beams,

and when disengaged by the pins, permitting the outer beams to be adjusted independently of each other to and from the inner beams. It is seen, therefore, that these two connecting devices 24 and 25, while causing all the beams to be moved positively with the lateral movements of the beam support, permit of an adjustment of the inner beams to and from each other, carrying with them the outer beams, and permit also of the adjustment of the outer beams to and from the inner beams independently of each other.

The beams are suspended in such manner that they may be raised and lowered independently of each other, and also in unison. The independent control is effected by four hand levers 26, 27, 28 and 29, pivoted to segment frames fixed at intervals, corresponding to the location of the several beams, to a square rock-shaft 30, extending along the upper side of the axle-member 2 and mounted at its ends in bearings 30^a, the said shaft being rocked and adjusted to different positions by means of a hand lever 31 fixed to the shaft and provided with a locking dog adapted to engage in notches in a segment frame 31^a fixed to the machine frame. The four hand levers 26, 27, 28 and 29 are connected to their respective beams by suspension rods 26^b and 27^b, etc., jointed at their upper ends to the levers and passed at their lower ends through holes in the beams, their lower ends having fixed to them heads which, when the rods are raised, will engage and elevate the beams. Above the beams the rods are encircled by spiral springs bearing at their upper ends against heads on the rods, and at their lower ends against upper sides of the beams, as a result of which construction, when the hand levers are depressed, the beams will be lowered and subjected to a yielding pressure, and when the hand levers are raised, the beams will be elevated. The beams are raised and lowered in unison by the operation of hand lever 31, which will rock square shaft 30 and correspondingly rock all the segments for the individual levers which, and owing to their locked connection with the levers, and the connection of the latter with the beams, will raise and lower the beams together. The elevation of the beams in this manner in unison is assisted by the longitudinal spiral spring 32 connected at its rear end to an arm 33 of the rock shaft, and at its forward end to the frame bar 13.

It will be observed from the construction described that the beams are horizontal from end to end, being connected at their forward ends to the depressed portions of the beam support, to the ends of which, draft links 40 are connected through the medium of the yoke frames 20, as shown in Fig. 4, and consequently the draft is applied at a low point in line with the beams, which will

have the result of giving better penetration to the cultivating devices, the fore and aft parallel links on brackets 17, 17^a and 22, by which the beam support is connected with the frame and guided in its transverse movements, being inclined downwardly from their rear ends, where they have connection with the elevated axle member, to their forward ends, where they have connection with the depressed portions of the beam support.

Having thus described my invention, what I claim is:—

1. In a wheeled cultivator, the combination with the frame, of a transversely movable beam support, a lever mechanism sustained by the frame and operatively connected with said beam support for shifting the same laterally, beams carried by the support and movable thereon laterally with relation to the support, a connecting member between the frame and beam support movable laterally with the beam support, and a lever mechanism carried by said connecting member and operatively connected with the beams for adjusting the same laterally on the beam support.

2. In a two-row wheeled cultivator, the combination with a frame, of a single beam support sustained by said frame and movable bodily as a unit transversely thereof, a lever mechanism for controlling said movements of the beam support, two pairs of cultivator beams carried by said beam support and movable transversely thereon with reference to the support, a lever mechanism operatively connected with the inner beam of each pair for adjusting said pairs to and from each other simultaneously, and adjustable connections between the individual beams of each pair; whereby while the distance between the pairs of beams, and the distance between the individual beams of each pair may be varied independently, the entire set of beams may be shifted transversely in their adjusted position.

3. In a wheeled cultivator, the combination with the frame, of a transversely movable unitary beam support, beams carried by the support, a horizontally disposed foot lever mounted to rock on an axis between its ends, and connecting devices between said foot lever respectively on opposite sides of its axis and the beam support; whereby by the actuation of the foot lever, the beam support is subjected to both a pulling and pushing force acting in the same direction.

4. In a wheeled cultivator, the combination with the frame, of the transversely movable unitary beam support, beams connected with the support, a horizontally arranged foot lever pivoted between its ends to rock on a vertical axis, and rods connected at their rear ends to the foot lever on opposite sides of its axis respectively, and at their forward ends to the beam support; whereby

- 4.
- by the actuation of the foot lever, the beam support is subjected to both a pulling and pushing force acting in the same direction.
5. In a wheeled cultivator, the combination with the frame, of a transversely movable unitary beam support, beams connected therewith, a horizontally disposed foot lever pivoted between its ends to rock on a vertical axis, and connecting rods between the foot lever and the beam support, said rods having their rear ends connected with the foot lever on opposite sides of the axis, whence they extend outwardly from each other, and have their forward ends connected with the beam support.
6. In a wheeled cultivator, the combination with the frame, of a unitary beam support provided with elevated portions to straddle the plants and depressed portions for the attachment of the beams, beams connected with the depressed portions of the support, a horizontally disposed foot lever pivoted between its ends to rock on a vertical axis, and rods connected with the lever on opposite sides of its axis respectively, and with the elevated portions of the beam support.
7. In a wheeled cultivator, the combination with the frame, of a transversely movable beam support, beams connected therewith, a longitudinally extending link 22 having pivotal connection with the frame and with the beam support, a foot lever mounted on said link, and connections between the foot lever and the beam support.
8. In a wheeled cultivator, the combination with the frame, of a transversely movable beam support, longitudinally extending brackets 17 and 17^a connecting the ends of the beam support pivotally with the frame, a central longitudinally extending link 22 pivotally connected with the frame and with the beam support, and a foot lever mechanism mounted on the central link and operatively connected with the beam support.
9. In a wheeled cultivator, the combination with the frame, of the transversely movable beam support, beams carried thereby, yoke frames 20 on the ends of the support, vertical links pivoted to the machine frame and to the yoke frames, rearwardly extending arms on the yoke frames, and longitudinally extending parallel brackets pivoted at their rear ends on the machine frame and at their forward ends between the arms on the yoke frames; whereby the beam support in its shifting movements will be maintained parallel with the axle, thereby causing the cultivator beams to face squarely in the line of draft.
10. In a wheeled cultivator, the combination with the frame, of the transversely movable beam support, beams carried by said support and movable thereon transversely, a longitudinally extending link piv-

- oted to the frame and to the beam support, and movable with the latter transversely devices connecting the beams and mounted on the transversely movable longitudinal link, said connecting devices being constructed to be actuated to move the beams to and from each other, and means for controlling the transverse movements of the beam support.
11. In a wheeled cultivator, the combination with the frame, of the transverse beam support, two pairs of beams carried by said support, and movable in unison therewith and also relatively thereto connecting devices between the inner beams constructed to be actuated to adjust said pairs of beams to and from each other and relatively to the beam support, and adjustable devices connecting the inner beams with the outer beams; whereby the adjustments of the inner beams relatively to each other will cause the outer beams to be correspondingly adjusted and preserve their relations to the inner beams.
12. In a wheeled cultivator, the combination with the frame, of the transversely movable beam support, two pairs of beams mounted on said support, means for controlling the transverse movements of the beam support, a longitudinally extending link pivotally connected with the frame and with the beam support, and movable therewith transversely devices sustained by said link and connecting the inner beams together, and connections between the inner and outer beams.
13. In a wheeled cultivator, the combination with the frame, of the transverse beam support, beams mounted on said support and movable transversely thereon, transversely extending links jointed at their outer ends to the beams and jointed together at the inner ends, and means for varying the angular relations of the links.
14. In a wheeled cultivator, the combination with the frame, of the transverse beam support, beams mounted thereon and movable transversely with relation to the support, transversely extending links pivoted at their outer ends to the beams on longitudinal axes and jointed together at their inner ends on a longitudinal axis, and means for raising and lowering the inner jointed ends of the links.
15. In a wheeled cultivator, the combination with the frame, of a transverse beam support, beams sustained by said support and movable thereon transversely, transversely extending links jointed at their outer ends to the beams on longitudinal axes, a hand lever, and a vertically movable arm on the lever jointed to the inner ends of the links.
16. In a wheeled cultivator, the combination with the frame, of a transverse beam support, beams sustained by the support

and movable transversely thereon, transversely extending links pivoted at their outer ends to the beams on longitudinal axes, and a lever mechanism jointed to the 5 inner ends of the beams on a longitudinal axis.

17. In a wheeled cultivator, the combination with the frame, of a transversely movable beam support, forwardly and downwardly extending brackets having a pivotal connection at their upper ends with the frame on vertical axes, and at their forward lower ends having pivotal connection with

the beam support, draft connections attached to the beam support at the points of 15 connection with the brackets, horizontal beams connected at their forward ends to the beam support, and means for controlling the lateral movements of the support.

In testimony whereof I hereunto set my 20 hand this 14th day of September, 1908, in the presence of two attesting witnesses.

ALEXUS C. LINDGREN.
